UNITED STATES PATENT OFFICE.

JOHN NEUMAIER, OF DAYTON, OHIO.

PROTRACTOR.

1,387,297.

Specification of Letters Patent.

Patented Aug. 9, 1921.

Application filed June 6, 1919. Serial No. 302,315.

To all whom it may concern:

Be it known that I, JOHN NEUMAIER, a citizen of the United States, residing at Dayton, in the county of Montgomery and State of Ohio, have invented certain new and useful Improvements in Protractors, of which the following is a specification.

The object of this invention is to provide a new and improved form of protractor for 10 use in a drafting room or a machine shop.

Another object of this invention is to provide the protractor with an extension straight edge that is adjustable and that will enlarge the range of use of the protractor.

15 These and other objects of the invention will be fully shown in the drawings, described in the specification and pointed out in the claims at the end thereof.

In the drawings,

20 Figure 1 is a plan view of the protractor embodying my invention.

Fig. 2 is a detail view of the extension.

Fig. 3 is a section on the line 3^x—3^x of Figs. 1 and 2.

25 Fig. 4 is a section on the line 4^x—4^x of Fig. 1.

In the several figures of the drawings, like reference numerals indicate like parts.

The invention of this application is an 30 improvement on the invention shown in my prior application No. 279,825, Feb. 28, 1919.

In the drawings, reference numeral 1 indicates one arm of the protractor and 2 and 3 indicate the other arms of the protractor, 35 the arm 1 extending from one side of the center and the arms 2 and 3 extending from the other side of the center, all three of the arms swinging on the same center. Integral with the plate 1 is the dial plate 4, 40 which dial plate is provided with a series of holes 5, 5, therein, which holes are spaced equal number of degrees apart between centers, the unit of measurement preferably used being 10°.

45 Mounted above the plate 4 is the plate 6 adapted to swing independently around the center 7. This plate contains one large hole at 8 which is concentric with a series of holes 5, 5 on the plate 4. A pin 9 is provided which engages with the hole 8 and with any one of the holes 5 so that by shifting the plate 6 to any desired position on the plate 4 the two plates can be locked together by the pin 9 in that position.

55 Rigidly fastened to the arm 2 is the plate 10. This plate overlaps the plate 6 and is

intended to swing over the edge of it. In the plate 10 is provided a series of ten holes, which holes are concentric with the center 7 and are spaced certain distances apart. 60 In the plate 6 is also provided a series of holes, which holes are also concentric with the center 7 and are spaced one degree farther apart between centers than are the holes in the series in the plate 10. The series of 65 holes in the plate 10 and in the plate 6 are placed at the same distance from the center 7. An arm 11 is provided having a pin 12 thereon, which pin is concentric with both series of holes in the plates 6 and 10. The 70 pin can pass through one hole of each series and normally passes through the 0 hole of both series in plates 6 and 10. When the pin is disengaged from the plates 6 and 10 the arm 2 may be shifted so as to move the 75 first hole on the plate 10 into position over the first hole on the plate 6, and the pin can then engage with these two holes to lock these two plates together, in which position the arm 2 will be advanced 1° beyond the 80 position which it occupied when the pin engaged the 0 holes of both plates. In like manner, the plate 10 may be advanced another step or steps so that the pin 12 will engage with any other pair of holes bearing the same number in the two plates and in this way measurements by single degree 85 units are secured, which measurements are in addition to the 10° units measured by the plate 6 on the plate 4.

The arm 3 normally abuts against the arm 2 and is held in close engagement therewith by the spring 13.

Overlapping the arms 2 and 3 is provided 90 the plate 14, which plate bears against a shoulder 15 on the arm 2 and bears against an anti-friction roller mounted on a pin 16 on the arm 3. The plate 14 is wedge shaped and has a scale thereon which is divided into sixty spaces of equal length, each of which 95 spaces represent one minute. The 0 mark on the plate 14 normally stands in line with the 0 mark on the arm 2. By moving the plate 14 down one space, the arms 2 and 3 will spread apart by an angle of one minute, the plate 14 being tapered at the right angle to secure this result. By moving the plate 14 five spaces the arms 2 and 3 will be 100 spread five minutes, etc.

The arm 3 is provided with a dove-tailed 110 groove as indicated at 17. Mounted to slide on the arm 3 is a plate 18 having a tongue

19 thereon which engages with the dove-tailed groove 17. This plate projects over the arm 3 and supports an extension plate or straight edge 20 in the following manner. 5 The extension 20 has a dove-tailed groove 21 therein which is engaged by tongues 22, 31 and 32 below the plate 18. The tongue 22 is loose and is supported by a pin 23 and thumb nut 24. A washer 25 is interposed 10 between the thumb nut 24 and the plate 18. By screwing down on the thumb nut 24, the pin 23 and tongue 22 are drawn up, the tongue raising the plate 20 against the plate 18 and holding it firmly in place thereunder. 15 The thumb nut 24 can be loosened which will in turn loosen the tongue 22 and permit the plate 20 to slide thereon to any desired position in which it may then be clamped by tightening up on the thumb nut 24. 20 The tongues 31 and 32 are rigid with the plate 18.

The arm 1 is grooved in the same manner and the plates 18 and 20 may be removed from the arm 3 and engaged with the arm 25 1 in the same manner as above described.

The arm 3 is provided with a set screw 26 and the arm 1 is provided with the set screw 27. The plate 18 is recessed at 28 and 29 so as to make slotted engagement with 30 the screw and will be clamped in place thereby, it being understood that the plate 18 is in proper position when it bears against the set screw.

It will be understood that this protractor 35 will be used without the extension for measuring ordinary angles formed at one side of their common pivot center with the sides of one of the arms. The extension will be used for measuring the complement of the angle 40 formed on the other side of their common pivot center. If the arm 1 is used as the base and the extension is applied to the arm 3, the extension 20 will measure the same angle measured by the arm 3. If the extension 45 is applied to the arm 1 and the arm 3 is used as a base the same result will be secured but the position of the instrument can thereby be reversed and readings taken 50 therefrom with the same facility in either case.

I claim:

1. A protractor having two arms thereon pivoted on a center and extending normally in the same direction therefrom, the outside 55 of each arm being parallel to the outside of the other arm when in zero position, one of said arms having its inner edge extending radially from the center and the other arm having its inner edge normally parallel to 60 and spaced apart therefrom with an open space between them, an extension on one of said arms extending in the opposite direction, said arms being adapted to measure angles on one side of the common pivot of 65 the arms, the extension being used to meas-

ure the same angle at the other side of the common pivot of the arms.

2. A protractor having two arms thereon pivoted on a center and extending normally in the same direction therefrom, an extension on one of said arms extending in the opposite direction, said arms being adapted to measure angles on one side of the common pivot of the arms, the extension being used to measure the same angle at the other side 70 of the common pivot of the arms, said extension being applicable to either arm, the arm carrying the extension being used as the side and the other arm being used as the base of 75 the protractor.

3. A protractor having two arms thereon pivoted on a center and extending normally in the same direction therefrom, an extension on one of said arms extending in the opposite direction, said arms being adapted 80 to measure angles on one side of the common pivot of the arms, the extension being used to measure the same angle at the other side of the common pivot of the arms, said extension being applicable to either arm, the arm carrying the extension being used as the side and the other arm being used as the base of 85 the protractor, one of said arms having a dovetail groove thereon, a plate having a tongue thereon adapted to engage with said 90 groove, means for clamping a section of said tongue in said groove, an extension arm mounted to slide on said plate in parallel relation to the arm supporting the plate.

4. A protractor having two arms thereon 95 pivoted on a center and extending normally in the same direction therefrom, an extension on one of said arms extending in the opposite direction, said arms being adapted to measure angles on one side of the common 100 pivot of the arms, the extension being used to measure the same angle at the other side of the common pivot of the arms, said extension being applicable to either arm, the arm carrying the extension being used as the side and the other arm being used as the base of 105 the protractor, each of said arms having a dovetail groove therein, a plate having a tongue thereon adapted to engage with the groove in either arm, means for clamping a 110 section of said tongue in said groove, an extension arm mounted to slide on said plate in parallel relation to the arm supporting the plate, said protractor being made reversible by transferring the plate and extension from one arm to the other.

5. A protractor having two arms thereon pivoted on a center and extending normally in the same direction therefrom, an extension on one of said arms extending in the 115 opposite direction, said arms being adapted to measure angles on one side of the common pivot of the arms, the extension being used to measure the same angle at the other side of the common pivot of the arms, said exten- 120

sion being applicable to either arm, the arm carrying the extension being used as the side and the other arm being used as the base of the protractor, one of said arms having a 5 blind dovetail groove therein, a binding screw located at the end of said groove, a plate having a tongue thereon adapted to engage with said groove, said plate having a forked end adapted to engage under the 10 head of said screw to be clamped in place thereby.

6. A protractor having two arms thereon pivoted on a center and extending normally in the same direction therefrom, an extension 15 on one of said arms extending in the opposite direction, said arms being adapted to measure angles on one side of the common pivot of the arms, the extension being used

to measure the same angle at the other side of the common pivot of the arms, said extension being applicable to either arm, the arm carrying the extension being used as the side and the other arm being used as the base of the protractor, one of said arms having a blind dovetail groove therein, a binding 20 screw located at the end of said groove, a plate having a tongue thereon adapted to engage with said groove, said plate having a forked end adapted to engage under the head of said screw to be clamped in place 25 thereby, an extension arm mounted to slide on said plate in parallel relation to the arm supporting the plate.

In testimony whereof I affix my signature.

JOHN NEUMAIER.
